DESIGN FOR A CLIP

Bertha T. Barrett, Brooklyn, and Elizabeth Johnson, New York, N. Y.

Application September 29, 1937, Serial No. 71,864

Term of patent 3½ years

To all whom it may concern:

Be it known that we, Bertha T. Barrett and Elizabeth Johnson, both citizens of the United States and residents, respectively, of New York city (Borough of Brooklyn), in the county of Kings and State of New York, and New York city (Borough of Manhattan), in the county and State of New York, have invented a new, original, and ornamental Design for a Clip, of which the following is a specification, reference being had to the accompanying drawing, forming a part thereof, and of which Figure 1 is a view in front elevation; Fig. 2 is a view in edge elevation; Fig. 3 is a view in rear elevation; and Fig. 4 is a view in rear elevation in open position, of a clip, showing our new design.

We claim:

The ornamental design for a clip substantially as shown.

BERTHA T. BARRETT.
ELIZABETH JOHNSON.
